BUTTON LOOP

Application filed June 6, 1930. Serial No. 459,473.

This invention relates to expandible button loops of one piece wire construction having its terminals movably connected by means of an attached member.

5 The objects of the invention are to provide a novel means for connecting the wire terminals of a button loop; to provide for a button loop an inserted link to which the loop terminals are pivotally secured to permit the 10 expansion and contraction of the loop; to provide a pivotally connected link with a seat for the shank of a button which seated therein maintains the loop inexpandible; and to provide a button loop the lateral expansion 15 of which is accompanied by relative axial distortion of side structures. With these and other objects in view the invention consists in the novel constructions, to be hereinafter described or claimed, for carrying 20 out the above stated objects and such other objects as hereinafter may be made to appear.

For a clear understanding of the character of the invention, reference is made to one 25 illustrative device embodying the novel features herein disclosed and illustrated by the accompanying drawing in which the Figure 1 is an elevation of a contracted button loop; the Figure 2 is a similar elevation, but of an 30 expanded button loop; and the Figure 3 is a side elevation of the same button loop, the Figure 4 being an elevation of a modified form of button loop.

The device as illustrated comprises the suspension loop 1, the button-receiving loop 2, 35 the normally restricted throat portion 3, and the button-retaining loop 4. The device is chiefly made of resilient wire of which a middle portion is bent to form the suspension loop 1, the other wire portions depending 40 therefrom to provide the spring side arms 5 and 6 cooperating to provide the axially associated loops 2 and 4 having the intermediate and normally restricted throat portion 3, the wire terminals 7 and 8 over-reaching 45 one beyond the other and each having at its extremity a bent tip 9 or 10 slightly extending in a right angled direction out of the plane of the button loop. The link 11 comprises preferably a sheet metal member having 50 an edge provided with the depression 12

within which the shank S of a button may be seated. Spaced bores 13 and 14 provided by the sheet metal link member 11 accommodate the bent tips 10 and 9, respectively, upon the assembly thereon of the link 11, and the tips 9 and 10 are so upset at their head positions as to provide a permanent assembly of the button loop parts as best illustrated by the Figure 3.

When the shank S of a button is in either 60 one or the other of the associated loops 2 or 4, as illustrated by the full and dotted positions thereof in the Figure 1, the normal effect 65 of the resilient side arms 5 and 6 is to maintain erect the link 11 so that the depression 12 is in readiness to receive the shank S of a button, but as the shank S is urged through the restricted throat portion 3 thereby expanded, as illustrated by the Figure 2, the link 11 is laterally tipped along the plane of 70 the button loop, and the side arms 5 and 6 are relatively moved from their normal positions in axial directions tending to give the button loop structure a distorted appearance as exaggeratedly illustrated by the Figure 75 2. The definite tendency of the resilient button loop structure to return to its normal condition combines the force of the lateral and axial tensions of the arms 5 and 6 to provide 80 a sturdy action not usually attained by an ordinary expanding and contracting button loop. The shank S seated within the depression 12 of the erect link 11, as illustrated by the dotted position thereof in the Figure 1, thereby maintains an inexpandible button 85 loop for the reason that the link 11, thus engaged by the shank S, cannot be tipped to permit the expansion of the button loop.

The Figure 4 is an elevation of a modified structure of the preferred form of button 90 loop above described, the modified structure, as in the preferred form, having the suspension loop 1, the axially associated loops 2 and 4 intermediately provided with the restricted throat portion 3, the side arms 5 and 6 however having terminals 7A and 8A, respectively, upon one and the same side of the structure, the link 11A being there inserted and assembled to the loop structure by means 95 of the right angled bent tips 9A and 10A of 100

the terminals 7 and 8, as in the preferred form, being pivotally engaged and upset in the bores 13A and 14A provided by the link 11A. By the insertion of the link 11A the button loop of the modified form, as in the preferred form, is made expansible, the shank S of a button, urged through the restricted throat portion 3, laterally forcing the arms 5 and 6 against their spring tension to assume expanded positions, the relative movement of the arms 5 and 6 being permitted by reason of the pivotally linked insertion of the link 11A. As in the preferred form, the link 11A of the modified form must of necessity axially distort the button loop structure as it pivotally yields upon the forced expansion of the restricted throat portion.

I claim:

1. A button loop comprising a suspension loop having spring arms depending therefrom and providing in axial alignment associated loops having an intermediate restricted portion, the arms having terminals normally over-reaching one behind the other and a link pivotally connected to said terminals, said link being provided with a seat for the shank of a button, the link tipping yieldingly to permit the expansion of the restricted portion;
2. A button loop comprising a suspension loop having spring arms depending therefrom and providing in axial alignment associated loops having an intermediate restricted portion, the arms having terminals normally over-reaching one beyond the other and a link pivotally connected to said terminals, said link being provided with a seat for the shank of a button, the link tipping yieldingly to permit the lateral expansion of the restricted portion only upon a slight axial distortion of the button loop structure;
3. A button loop comprising a suspension loop having arms depending therefrom and providing axially associated loops in a common plane and having an intermediate restricted portion, the arms having terminals and a link of one piece of material pivotally connected to said terminals, said link being movable only in the plane of the loops to permit the expansion of the restricted portion;
4. A button loop comprising a suspension loop having spring arms depending therefrom and providing axially associated loops in a common plane and having an intermediate restricted portion, the arms having terminals, and a sheet-metal connecting member so mounted upon the terminals as to have a tipping movement only in said plane to permit the lateral expansion of the restricted portion only upon a slight axial distortion of the button loop structure;
5. A button loop comprising a suspension loop having spring arms depending therefrom and providing axially associated loops in a common plane and having an intermediate restricted portion, the arms having terminals and a link pivotally connected to said terminals, said link being movable only in said plane and providing a seat for the shank of a button, the link tipping yieldingly to permit the expansion of the restricted portion only upon the unseating of the shank.

JESSUP SALISBURY.

ate restricted portion, the arms having terminals and a one-piece sheet-metal link pivotally connected to said terminals, said link being movable only in said plane and provided with a seat for the shank of a button and permitting the expansion of the restricted portion only upon the unseating of the shank.
